[57] CLAIM

The ornamental design for saltwater fish lure, as shown and described.

DESCRIPTION

FIG. 1 is a perspective view of my design;
FIG. 2 is an elevation view of the design of FIG. 1 rotated about 90° along its vertical axis;
FIG. 3 is an elevation view of my design rotated 90° from the view of FIG. 2 and with an outer skirt removed;
FIG. 4 is a top plan view of the design of FIG. 1; and,
FIG. 5 is a bottom plan view of the design of FIG. 1.
